UNITED STATES PATENT OFFICE.

LEWIS TREVOR BAMFORD MATTHEWS, OF BIRMINGHAM, ENGLAND.

FIREPLACE.

1,101,303.

Specification of Letters Patent.

Patented June 23, 1914.

Application filed May 1, 1913. Serial No. 764,847.

To all whom it may concern:

Be it known that I, LEWIS TREVOR BAMFORD MATTHEWS, subject of the King of Great Britain, residing at 60 Newhall street, in the city of Birmingham, England, have invented certain new and useful Improvements in Fireplaces, of which the following is a specification, reference being had therein to the accompanying drawings.

10 This invention relates to improvements in and appertaining to open fireplaces and has for its object the provision of means whereby a gas stove can, as occasion requires, be brought into and out of position and flush 15 with the front of the fireplace. By this means a gas fire can be had in substitution for a coal fire and vice versa.

I am aware that it has been proposed to bring gas stoves into and out of position in 20 front of a fireplace by having a gas stove in a cavity or recess and hinging or raising the same into position but my invention consists in one form in providing the fireplace with an overhead track or rail below which 25 a self-contained gas stove can move laterally so as to fill up and fit the front of the fireplace and not protrude therefrom as a superimposed gas stove does. In other words when the gas stove is in position the 30 appearance is that of a gas fire and nothing else and when the gas stove is shut out of position there is nothing to indicate the use of such gas stove. In a modification the 35 fireplace is provided with a guiding rod and the bottom of the gas stove is provided with rollers as will be hereinafter described.

In carrying my invention into effect and in one form of same I provide at the top of the fireplace a suitable track or rails for 40 rollers carried by transverse carrier pins to run along. The gas stove is suspended by means of hooks or hangers to these carrier pins.

Situated in the middle of the supporting 45 tracks of the traveling way is a gas supply pipe carrying within it a sliding tube or pipe attached to the gas stove. One of the sides or panels of the fireplace (preferably the left hand side), is hinged to allow of 50 access to a recess provided at the side of the fireplace for the gas stove to take into and be shut away from view; the supporting track extends into this recess. By this 55 means a ready and convenient conversion of fire can be obtained as the gas stove can be

easily slid into or out of position. In a modification of my invention I provide the gas stove with a roller or rollers at its base for sliding into and out of position. In this case the top of the stove will be provided with a clip for taking onto a guiding rod situated on the top of the fireplace. The fret or stand of the fireplace, if provided with a platform, may, in this case, be grooved for the rollers or roller to take 60 into; otherwise the rollers will slide on the hearth tiles.

In the accompanying sheets of drawings Figure 1 is a front elevation of my improved fireplace showing the gas stove in position and with the brickwork broken away showing the recess and gas stove in dotted lines. Fig. 2 is a part sectional plan on dotted lines Y, Y, of Fig. 1. Fig. 3 is a sectional elevation on dotted lines X, X, of Fig. 1, 70 the grate however, being shown in side elevation. Fig. 4 is a sectional plan of fireplace on dotted lines Z, Z, of Fig. 1. Fig. 5 is a detached view in front elevation of the stove, Figs. 1 to 3, with sliding pipe attachment in front elevation. Fig. 6 is an 75 end elevation of the structure shown in Fig. 5, with top part partly in section. Fig. 7 is an enlarged side elevation of the upper 80 part of the stove, shown in Figs. 1 to 6, with its supports shown in section, and Fig. 8 is an enlarged sectional view showing the gas 85 supply pipe with sliding tube and union attachment. Fig. 9 is a modification of my invention showing the gas stove in position 90 with rollers at its base for sliding on the fret of the fireplace which may be grooved for that purpose. If there is no fret as in the case of some sunk fires, then the rollers will slide on the hearth tiles. In this case 95 the top of the stove is provided with eyes or slips for taking onto a guiding rod on the top of the grate. Fig. 10 is an enlarged view showing the slipping or guiding arrangements at top of stove shown in Fig. 9, and Fig. 11 is a further enlarged view 100 showing a cylindrical roller fitted into the bottom of the stove, shown in Fig. 9, and running along a groove in the fret of the grate.

In Figs. 1 to 7, the top 2 of the fireplace frame 1 is provided between its front and back portion 3, 4 with an L-shaped supporting track comprising L-shaped bars 5 with stop 6 said track extending beyond the fire- 110

place on its one side. The gas stove 7 is provided at its top 8 with hooks 10 for taking onto transverse pins 9 carried by rollers 11 on the supporting track as afore-
 5 said. A bridge portion 12 which helps to clamp the top of the fireplace frame and track together is provided with a screw eye 13 which carries the gas supply pipe 14. This stationary supply pipe is fitted to take
 10 a telescopically inserted sliding pipe 15 which connects through a union 16 with a further pipe 17 terminating in a tap 18 conveniently located for controlling the supply of gas to the stove. An elbow 15' connects
 15 the pipe 14 with a vertical pipe 15² which is connected with a main gas supply pipe 15³. The panel 19 at one side of the fireplace is hinged and provided with a catch 20, as shown in Fig. 4, for allowing the
 20 stove to be pushed back along its extended track by its inner end abutting against a shoulder of the union 16 into a recess 21 provided for it at the side of the fireplace.

In Figs. 9 to 11, the stove 7 instead of being suspended and slid along the track 5, is provided at its base with rollers 23 for traveling along the fret 22 of the fireplace 1, which has an extended portion 24 with stop 25 and which is shown grooved in Fig.
 25 11 for the purpose. In this case the stove is provided with clipping hooks 26 for taking onto a guiding rail 27 situated on the top of the fireplace. The side of the fireplace is hinged as before and the arrangement of gas supply pipe with sliding tube connected to stove is the same as previously.
 30 35

Having now described my invention I declare that what I claim is:

1. A fireplace provided with a recess located at the side of the fireplace, a hinged panel closing said recess and an overhead traveling way, located above the fireplace and in the recess, in combination with a gas stove provided with guiding devices engaging said way and an extension gas pipe connected to the gas stove and to a stationary supply pipe, substantially as described. 40 45

2. The combination with a fireplace provided with a recess at the side and a hinged side or panel closing said recess, said fireplace and recess being fitted at top with a traveling way, of a gas stove provided with hooks, and carrier pins mounted on the traveling way and engaged by said hooks, said gas stove being fitted with a gas pipe, 50 55 substantially as described.

3. A fireplace with a recess at the side and a hinged side or panel closing said recess, with horizontal supporting and guiding means located above the fireplace and recess, a gas stove movable horizontally, and means for supporting said stove from said supporting and guiding means and allowing it to be moved in and out of said recess, 60 65 substantially as described.

In testimony whereof I have affixed my signature in presence of two witnesses.

LEWIS TREVOR BAMFORD MATTHEWS.
